UNITED STATES PATENT OFFICE.

FRANK H. WHEELOCK, OF ST. PAUL, MINNESOTA, ASSIGNOR OF ONE-HALF
TO GEORGE W. WALSH, OF SAME PLACE.

MEANS FOR PREVENTING SLIPPING OF CAR-WHEELS UPON GRADES.

SPECIFICATION forming part of Letters Patent No. 601,296, dated March 29, 1898.

Application filed January 15, 1897. Serial No. 619,398. (No model.)

To all whom it may concern:

Be it known that I, FRANK H. WHEELOCK, of St. Paul, Ramsey county, Minnesota, have invented certain Improvements in Means for Preventing Slipping of Car-Wheels upon Grades, of which the following is a specification.

My invention relates to improvements in means for preventing the slipping of car-wheels upon grades.

To this end my invention consists in arranging upon the grades of the road-bed a pair of toothed rails or racks adapted to engage with cog-wheels upon the car-truck axle, thus forming a positive intermeshing connection. I also arrange upon the road-bed an additional pair of track-rails and provide the car-truck with an additional set of wheels adapted to run upon said rails, the wheels and rails being so arranged that the main truck-wheels will be lifted off from and remain free of the main rails until the end of the grade is reached.

In the accompanying drawings, forming part of this specification, Figure 1 is a cross-section of the road-bed, showing a car-truck and my features of invention; and Fig. 2 is a conventional view showing the toothed rail or rack engaging with a cog-wheel upon the car-truck.

In the drawings, 2 represents the ordinary rails arranged in the road-bed A. Arranged inside the rails 2 upon the road-bed are suitable beams 3, upon which are secured a pair of rails 4 and a parallel toothed rail or rack 5, provided with teeth 6. The beams 3 are arranged upon the inclines of the road-bed, as shown in Fig. 2. Secured upon the axle 7 of the car-truck, inside the wheels 8, are the cog-wheels 9 and the supplemental truck-wheels 10.

As shown in Fig. 1, the rails 4 are on a con-

siderably higher level than the main rails 2, so that as the car travels up or down the incline the main wheels 8 are lifted from their tracks, the lower and upper ends of the inner tracks being inclined, so as to gradually lift the car. As the supplemental wheels 10 begin to ride upon the inner rails 4 the cog-wheels 9 will engage, as shown, with the track 50 5. Slipping of the wheels upon the rails is thus prevented while the car is traveling up the incline, since the cog-wheels will not be freed from the racks until the end of the rack at the top of the incline is reached. 55

This invention is particularly adapted for use in electric street-car systems. A frequent source of trouble in the ordinary electric street-car systems is the slipping of the truck-wheels upon the track in traveling up or down grades when the brakes are set, especially when there is a film of ice upon the rails. With my invention this trouble is entirely obviated. When the brakes are set, the car is compelled to remain stationary by 65 reason of the gears upon the axle intermeshing with the racks.

What I therefore claim as new is—

The combination with the main track-rails, of the elevated racks adjacent thereto, the supplemental rails 4, between and adjacent to the racks, and the truck-axles having the main wheels on the outer ends, the cog-wheels on the axle at opposite ends adjacent the main wheels, and the supplemental wheel 10 75 at the side of the cog-wheels, substantially as described.

In testimony whereof I affix my signature in presence of two witnesses.

FRANK H. WHEELOCK.
